UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

CASTING PUMP OPERATING MEANS

Original application filed August 28, 1925, Serial No. 53,182. Divided and this application filed May 1, 1929. Serial No. 359,565. Renewed April 16, 1931.

This is a division of my application for patent, Serial No. 53,182, filed August 28, 1925 on a motor operated casting device.

This invention relates to a pump especially for filling stereotype printing plate molds, although capable of use for other purposes.

The principal objects of the invention are to provide for the operation of the pump by power-operated means, and the automatic shutting off of said means when the desired object has been accomplished so as not to require attention by the operator for the latter purpose.

Other objects and advantages of the invention will appear hereinafter.

Reference is to be had to the accompanying drawings, in which

Fig. 1 is a plan of a stereotype plate casting pump constructed in accordance with this invention, shown with the mold closed and ready for filling, and

Fig. 2 is a side view of the pump mechanism partly in section on the line 2—2 of Fig. 1.

Heretofore it has been customary to operate the pump for filling stereotype plate molds with metal by a continuously operating motor from which the pump is disconnected to stop the pump. This invention is designed for use on a machine of this type in which the motor itself is stopped whenever the pump is to be stopped.

The pump P for supplying metal to the mold may be of the usual or any desired type, except that it has the usual piston 17 and piston rod 16 adapted to be operated vertically to force enough metal upwardly through the spout 11 to cast a plate at one operation of the piston.

I use a motor 12 connected to a worm 13 which operates a segmental worm wheel 14. A lever 15 turns with the wheel and thus raises the piston rod 16 and the piston 17 or lowers them. It will be understood that turning the segment 14 in one direction raises the piston and turning it back lowers it, and that in the latter case enough metal is forced out of the pump chamber 18 into the mold to cast a complete plate as is well understood in this art.

The motor 12 is provided with a switch 8 operated by an arm 19 and by a link 20 and handle grip 21. The lever 15 is equipped with two pins 9 and 10 which cause the switch handle to turn when the piston has reached its extreme position at either end of the stroke.

The operation of this part of the device is very simple. After the mold C B is closed as shown in Fig. 1 the operator pulls the handle grip 21 forward. This causes the switch 8 to close and the motor 12 to raise the pump piston. At the end of the pump stroke the parts 19, 20 and 21 are moved past their original position by the pin 9 acting on the switch handle 19. In this case the motor 12 instead of being stopped, is reversed as the pin 9 moves the handle 19 beyond neutral into its extreme position. The piston is returned to its original position, after having forced a charge of metal into the mold. At the end of the reverse stroke, the pin 10 moves the switch handle back into neutral position and stops the motor and pump in the position shown in Fig. 2.

When the plate has set, the operator causes the casting box to open so that the plate can be removed and the matrix changed if desired. No manipulation of the handle 21 is necessary. In this way the operation required for charging the mold is controlled by the handle 21 and the stopping of the parts is automatic so that no attention is required except to start them. This simplifies the operation considerably and reduces the amount of attention and supervision required in the casting of plates in small plants.

Although I have illustrated and described only a single form of the invention I am aware of the fact that modifications can be made therein by any person skilled in the art without departing from the scope of the invention as expressed in the claims. Therefore, I do not wish to be limited in these respects, but what I do claim is:

1. The combination with a stereotype casting box and power-operated means for opening and closing it, of a pump for intro-

ducing metal into the mold, power-operated means for operating the pump, an electric switch for starting the said last named power-operating means, and means whereby when the pump has performed a complete cycle of operations to fill the mold with a charge of metal the power-operated means will be shut off automatically.

2. The combination with a stereotype plate casting mold, of a pump having a spout adapted to conduct metal into said mold, said pump having a piston movable to conduct a full charge of metal into the mold, an electric motor having means for operating the piston of the pump, means for connecting said motor with a source of power, and automatic means for disconnecting the motor from the power when the piston has been operated through a complete stroke in both directions.

3. The combination with a stereotype plate casting mold, of a pump for supplying metal thereto, comprising a piston movable throughout a stroke up and down to furnish the mold with a complete charge of metal, a motor having a worm connected therewith, a gear segment adapted to be operated by said worm, a shaft on which the gear segment is fixed having an arm connected with the piston for operating it, hand-operated means for connecting the motor with a source of power to rotate it in a direction to raise the piston, and automatic means for reversing the motor when the piston has been raised and the gear segment has been turned through a complete stroke thereby causing the gear segment to turn back and the piston to move back to normal position and fill the mold with metal.

4. The combination of a pump, a motor having a worm connected therewith, a gear segment adapted to be operated by said worm, hand-operated means for connecting the motor with a source of power to rotate it in one direction, and means for reversing the motor when the gear segment has been turned through a complete stroke, thereby causing the gear segment to turn back to normal position.

5. The combination of a pump, a motor having a worm connected therewith, a gear segment adapted to be operated by said worm, the gear segment having an arm connected with the piston for operating it, hand-operated means for connecting the motor with a source of power to rotate it in a direction to raise the piston, and means for reversing the motor when the piston has been raised and the gear segment has been turned through a complete stroke, thereby causing the gear segment to turn back and the piston to move back to normal position.

6. The combination of a pump, a motor having a worm connected therewith, a gear adapted to be operated by said worm, the

gear having an arm connected with the piston for operating it, hand-operated means for connecting the motor with a source of power to rotate it, and means for reversing the motor when the gear has been turned 70 through a complete stroke thereby causing the gear to turn back and the piston to move back to normal position.

In testimony whereof I have hereunto affixed my signature. 75
